UNITED STATES PATENT OFFICE.

OLIVER M. EDWARDS, OF SYRACUSE, NEW YORK.

WINDOW.

SPECIFICATION forming part of Letters Patent No. 655,382, dated August 7, 1900.

Application filed July 1, 1895. Serial No. 554,671. (No model.)

To all whom it may concern:

Be it known that I, OLIVER M. EDWARDS, a citizen of the United States, residing at Syracuse, county of Onondaga, and State of New York, have invented certain new and useful Improvements in Windows, of which the following is a full, clear, and exact description, reference being had to the drawings accompanying and forming a part of the same.

My invention relates to devices employed for holding window-sashes in desired positions, releasing the same, and under some circumstances automatically moving the same in one direction when released, and has for its object the provision of means simple in construction, effective in operation, durable in use, and easy to attach in place.

My invention consists in the combination of compound and stationary stops with a window, means for operating the movable members of the compound stops to permit the window-sash to move, and a locking device engaging directly with the window-sash and operated to unlock the sash by the movement of the means which operate the movable members of the compound stops, as well as in certain other novel and useful combinations of parts, all of which will be herein-30 after fully described, and pointed out in the claims.

The accompanying sheet of drawings illustrates one form in which my invention can be carried out, and like letters of reference wherever they occur indicate corresponding parts in all of the figures.

Figure 1 is a front elevation of a window provided with my improvements. Fig. 2 is a vertical sectional view of the same on line 2 2 of Fig. 1 looking in the direction of the arrows, with a large part of the outer covering or stationary portion of one of the window-stops removed. Fig. 3 is a vertical sectional view on line 3 3 of Fig. 1 looking in the direction of the arrows. Fig. 4 is a cross-sectional view on line 4 4 of Fig. 1 looking downward, with a portion of the window-sill removed. Fig. 5 is a cross-sectional view on line 5 5 of Fig. 1 looking downward, with the window-sash omitted and a portion of the frame broken away and also with the portion

of the window-sill in place which is not shown in Fig. 2. Fig. 6 is a perspective view of a part at one corner of the window, showing the connections between the several parts. Fig. 7 is a longitudinal sectional view on line 7 7 of Fig. 5, showing some of the parts in full. Fig. 8 is a cross-sectional view on line 8 8 of Fig. 5, showing some of the parts in full. Fig. 9 is a plan view of a sash-lock looking from the under side thereof. Figs. 7, 8, and 9 are on an enlarged scale from that of the other figures of the drawings.

A is the glass of the sash B of the window, and C is the frame thereof. The sash B is arranged to slide up and down in the usual manner, and as here shown the sash is provided with a web D, attached at one end to the upper rail of the sash and at its other end to a spring-roller in a well-known manner. The spring carried by the roller has sufficient tension to move the sash in the opening direction whenever it is freed from the devices which hold it in the desired position.

I have shown a web and a spring-roller for opening the window; but it is obvious that cords and weights may be employed, if desired, with the same effect and without departing from the substance of my invention.

The general construction, arrangement, and operation of the stationary and compound stops relatively to the frame and sash of the window are similar to that shown in Figs. 5, 6, and 7 of a previous patent of mine dated September 13, 1892, and numbered 482,344; but there are certain respects wherein the window herein shown and described differs from the window found in my said patent. In my present window, as in that of said patent, there are stationary and compound stops, the latter being arranged to be moved to permit the window to move freely in the opening direction. These compound stops preferably consist of two parts, one of which serves simply as a covering or finishing piece for the other, and they are here so shown.

E E are compound stops, and as here shown consist of the covering-piece E' and the other or operative portion or movable member E². The covering-piece E' is preferably made out of wood and of a kind to correspond with the trim of the car or other structure in which

the window is to be used. The part E² is preferably made out of metal, and consists of a bar or strip *e*, which is to be attached to the frame C of the window. To this bar *e* there is attached a second bar of metal *e'*, preferably of the angle form, as seen in Fig. 6, by means of links *e²* *e³* and a spring or springs *e⁴*. This angle form of movable member has been found in practice to be cheap in construction, effective in use, and easy to keep in repair and in proper working order. This construction of movable member operates to hold the window-sash in the desired positions in substantially the same manner as do the movable stops in Patent No. 482,344. Hence I will only briefly describe their operation here. The links *e²* and *e³* are arranged inclined, as shown, with the spring or springs *e⁴* arranged so that their tension tends to move the bar *e'* upward and outward or in a direction to bring the links *e²* *e³* at right angles to the bar *e*, thus causing the bar *e'* to bear against the sash and force it against the stop arranged opposite thereto. This is a simple construction and it has been found to work well in practice. As here shown, the link *e³* is provided with an extension *e⁵*, so that the link forms one part of an angle-lever, by means of which the link *e³*, the bar *e'*, and link *e²* can be moved against the stress of the spring *e⁴* when the window is to be opened. The lower end of the extension *e⁵* connects with one end of a lever *e⁶*, which, as herein shown, is pivoted at *e⁷* to the sill of the window. This is the case with the extension *e⁵* at both edges of the sash, and the pivoted levers *e⁶* are preferably long enough to be connected together at their ends near the center of the window, so that both may be moved simultaneously by one hand of the operator. The mechanism by which this result is accomplished consists of two shafts *e⁸* *e⁹*, each of which is provided with two arms *e⁹* and *e¹⁰*, as shown, one of which, *e⁹*, enters a suitable slot or opening *e¹¹* in one of the levers *e⁶*, while the other, *e¹⁰*, extends through the window-sill into a convenient position for the operator to grasp when it is desired to operate the movable member. As herein shown, the pivoted levers *e⁶* are connected together so as to move in one direction only, and only one of the levers is provided with the slot *e⁹*; but the levers might be differently connected and differently operated, if desired, without departing from the substance of my invention.

It will be observed that the operator can by grasping the arms *e¹⁰* between the thumb and forefinger of one hand readily move them toward each other, and thus cause the arms *e⁹* to move the levers *e⁶* in a direction to move the bars *e'* away from the sash and permit it to be moved in an opening direction by the web and spring-roller provided for this purpose.

65 It has been found in practice that upon sudden jars, as in making up of trains, the compound stops will not in all cases hold the sash

in the closed position, but will sometimes when the shock is considerable release the sash sufficiently to allow the window to open a short distance. To obviate this, I provide a locking device F, which engages directly with the sash to lock the same in the closed position, but which is so arranged relatively to the pivoted levers *e⁶* and the shafts *e⁸* that upon the movement of the latter to open the window the locking device is operated to free the sash from its control. As here shown, the bolt *f* of the locking device can be moved in one direction against the stress of a spring *f'* without moving the levers *e⁶*, which spring tends to hold the bolt in the locking position. The bolt *f* consists, as here shown, of a pivoted lever one end of which is adapted to engage with a suitable recess or catch in the sash and also to be moved out of the path of the sash or catch when it is being closed. The opposite end of this bolt *f* is provided with a stud or projection *f²*, which is adapted to engage with one side of one of the levers *e⁶*, as is clearly seen in Fig. 4, so that when such lever is moved in a direction to open the window the pivoted lock-bolt *f* is likewise moved, so as to free the sash from its control and permit it to open.

It is desirable that the levers *e⁶* and their connected parts shall be concealed as much as possible, and as here shown they are located within the sill of the window; but it is obvious that they might be somewhat differently located and yet do the work that they do when arranged as shown. There is danger that cinders and dirt which are forced in between the sash and the stops will when the movable members are moved fall down in the openings through which the extensions *e⁵* of the links *e³* and the levers *e⁶* move. To provide against the accumulation of dirt and cinders in the recesses in which such extensions and levers move, I arrange caps or covers G, which are provided with openings adapted to receive the said extensions and cover up the openings in the portions of the stops through which these extensions pass to connect with the levers *e⁶*, as seen in Fig. 6, provision being made for these caps or covers G to move with the extensions *e⁵* as they move.

What I claim as new is—

1. The combination in a window, substantially as set forth, of a sash, a stop having a movable member, a pivoted lever, as *e⁶*, and a second pivoted lever, pivoted to move in a plane at an angle to that of the first lever, and connecting the movable member of the stop to the first pivoted lever, whereby the movement of the first pivoted lever causes the movable member of the stop to be moved.

2. The combination in a window, substantially as set forth, of a sash, a stop having a movable member, a pivoted lever, as *e⁶*, and an angle-lever pivoted at or near its angle to move in a plane at an angle to that of the first pivoted lever, and connecting the first pivoted lever to the movable member of the

stop, whereby the movement of the first pivoted lever causes the movable member of the stop to be moved.

3. The combination in a window, substantially as set forth, of a sash, a stop having a movable member, a lever pivoted to the sill of the window-frame to move in a plane at an angle to the plane of movement of the movable member, and means connecting the lever with the movable member of the stop, whereby the movement of the lever causes the member to be moved.

4. The combination, substantially as set forth, of a sash, a stop having a movable member, a pivoted lever, means connecting the lever with the movable member of the stop, and a cap or cover, as G, adapted to move with the means connecting the member with the lever, whereby dirt or cinders are prevented from passing from the recess in which the member moves into the recess in which the pivoted lever moves.

5. The combination, substantially as set forth, of a sash, a stop having a movable member, a pivoted lever, an angle-lever connecting the member with the pivoted lever, and a cover or cap, as G, adapted to receive a portion of the angle-lever and to move therewith, whereby dirt or cinders are prevented from passing from the recess in which the movable member moves into the recess in which the pivoted lever moves.

6. The combination, substantially as set forth, of a sash, a stop having a movable member, means for operating the movable member and a locking device arranged to engage with the sash, and also adapted to be moved out of engagement therewith upon the movement of said means, whereby the sash is released from the control of the locking device upon the movement of the means which operate the movable member to permit the sash to be moved.

7. The combination, substantially as set forth, of a sash, a stop having a movable member, a pivoted lever, means connecting the lever with the member, and a locking device arranged to engage with the sash, and also adapted to be moved out of engagement therewith, upon the movement of the lever,

whereby the sash is released from the control of the locking device upon the movement of the lever to operate the movable member to permit the sash to be moved.

8. The combination in a window, substantially as set forth, of a sash, two stops having movable members, two pivoted levers pivoted in the sill of the window-frame to move in a plane at an angle to the plane of movement of the movable members, means connecting the levers with the movable members, and means adapted to move the levers, whereby the movement of the levers causes the members to be moved.

9. The combination, substantially as set forth, two stops having movable members, two levers having one end of one connected to the corresponding end of the other and pivoted to move in a plane at an angle to that in which the movable member is moved, means connecting the levers with the movable members, and two shafts, each of which is provided with two arms, one arm of each shaft being connected with the levers, and the other arm of each shaft being adapted to be moved by the hand of the operator, whereby the movement of the two shafts causes the members to be moved.

10. The combination, substantially as set forth, of a sash, two stops having movable members, two pivoted levers connected together, means connecting the levers with the movable members, and two shafts, each of which is provided with two arms, one arm of each shaft being connected with the levers, and the other arm of each shaft being adapted to be moved by the hand of the operator, a locking device arranged to engage with the sash, and also adapted to be moved out of engagement therewith upon the movement of the levers, whereby the sash is released from the control of the locking device upon the movement of the shafts to operate the movable members of the stops to permit the sash to be moved.
